UNITED STATES PATENT OFFICE.

JEROME STIVERS, OF NEW ROCHELLE, NEW YORK.

DESIGN FOR A VEHICLE-BODY.

SPECIFICATION forming part of Design No. 27,664, dated September 21, 1897.

Application filed September 14, 1896. Serial No. 605,832. Term of patent 14 years.

To all whom it may concern:

Be it known that I, JEROME STIVERS, a citizen of the United States, residing at New Rochelle, in the county of Westchester and State of New York, have invented and produced a new and original Design for the Ornamentation of Vehicle-Bodies, of which the following is a specification, reference being had to the accompanying drawing, illustrating the same.

The drawing shows a side elevation of the body of a vehicle ornamented with the design.

The leading feature of the design is a vehicle-body the sides of which are ornamented by representations of the paraphernalia used in the game of golf, such as golf sticks and balls, but more particularly the sticks, the representations of the latter symmetrically arranged within the outline of the sides of the vehicle.

Another feature of the design is the seat-railing, which has its cross-piece, end uprights, and rounds ornamented with representations of golf-clubs or sections of the same, combined in a symmetrical arrangement.

Referring to the drawing, A designates the side of the body of a vehicle on which a portion of the design is shown. The portion of the design shown in this instance consists of the representation of two golf-clubs a a' , extending diagonally across the face of the side and passing each other near a central point a' . The representation shows the clubs arranged with their handles a^2 a^2 in the upper corners of the side and their heads a^3 a^3 in the lower

corners. Immediately below the point of cross of the clubs a representation a^4 of a golf-ball is shown. These representations may be made or shown either by painting or carving or by counterfeits of the articles themselves secured to the face of the side. The body is provided with a seat-rail B, also ornamented with representations of golf-clubs or sections of the latter. In the rail the two end uprights b and b' , which are curved to be symmetrical with the lines of the body, support the top cross-piece b^2 at its ends. This cross-piece is a counterfeit reproduction of a golf-club placed with its handle portion b^3 forward. The club end b^4 projects from the main handle in such a manner as to form somewhat of a continuation of the upright b' . The cross-piece b^2 is inclined downwardly toward its front end to better adapt it to its purpose. For strengthening purposes the cross-piece may be provided with a backing b^5 . Between the cross-pieces b^2 and b^6 and intermediate of the end uprights b and b' are placed rounds b^7 . The latter have a configuration similar to a section of the club end of a golf-stick. They are arranged with the club end down.

Having thus described my invention, what I claim, and desire to secure by Letters Patent, is—

The design for a vehicle-body substantially as shown and described.

In testimony whereof I hereunto affix my signature in the presence of two witnesses.

JEROME STIVERS
